CAR BOLSTER CONSTRUCTIONS

Stanley H. Fillion, Scarsdale, N.Y., assignor to Waugh Equipment Company, New York, N.Y., a corporation of Maine

Application July 1, 1958, Serial No. 745,852

5 Claims. (Cl. 105—226)

This invention relates to railway car underframe constructions and resides more particularly in a novel bolster for use in a cushion underframe, which includes a movable draft and buffering column extending from end to end of the underframe and connected to the car couplers. The new bolster is superior to prior bolsters for the same use in that it is stronger and more durable and, in addition, includes fewer parts and is less expensive to construct.

The bolsters now in use in railway cushion underframes commonly include a top cover plate extending across the underframe and a pair of bottom tie plates extending inward from opposite sides of the underframe and terminating outwardly from the center line of the underframe. The top cover and bottom tie plates are connected by pairs of diaphragm plates and a center filler casting closes the bottom of the space between the adjacent ends of the tie plates and has lateral extensions secured to the bottom of the plates. The casting supports the draft and buffering column, which is acted on by restoring springs resisting its movement in either direction from a central position produced by forces applied to the couplers, and the column has stops which engage the center filler castings and prevent the springs from going solid upon application of heavy blows to the column. The engagement of the stops on the column with the filler casting of a bolster tends to rotate the casting and, to resist such movement, the inner ends of the bottom tie plates of the bolster are connected to the top cover plate by torque arms and the casting has vertical extensions secured to the opposed faces of the arms. The torque arms extend from the adjacent end sill of the underframe to terminate either at the bolster or at the cross bearer inward therefrom.

The prior bolsters above described are expensive to construct because of the number of parts to be assembled and connected together. Also, the center filler castings with their two sets of extensions are difficult to produce and the torque arms add to the cost and the weight of the structure.

The present invention is directed to the provision of a novel bolster which overcomes the disadvantages of the prior bolsters in that it is stronger and more durable, is less expensive to construct, and avoids the necessity of employing torque arms.

For a better understanding of the invention, reference may be made to the accompanying drawings, in which

Fig. 1 is a fragmentary plan view, with parts broken away, illustrating a bolster constructed in accordance with the invention; and

Figs. 2 and 3 are sectional views on the lines 2—2 and 3—3, respectively, of Fig. 1.

In the drawings, the new bolster is shown as part of a railway car underframe, which includes end sills 10 extending transversely of the car at the ends of the underframe and side sills 11 extending between and connected to corresponding ends of the respective end sills. The underframe includes a bolster 12 adjacent the end sill

2

at each end of the underframe together with the usual cross bearers and cross ties.

Each bolster 12 includes a top cover plate 13, which lies in alignment with and extends between the top 5 horizontal flanges of the side sills 11. The bolster also includes a pair of bottom tie plates 14 and, in the construction shown, each tie plate is secured to the under surface of the bottom flange of a side sill and extends inward toward the center line of the underframe. Each 10 bottom tie plate has an outer section 14a, which lies approximately horizontal and parallel to the top cover plate and a middle section 14b, which extends downward at an angle from the inner end of section 14a. Beyond section 14b, each bottom plate has sections 14c and 14d extending upwardly the section 14c lying at an angle to the vertical, while section 14d is vertical. Beyond section 15 14d, the tie plate has an end section 14e, which lies against the under surface of the top cover plate and is secured thereto by welding indicated at 15. The sections 20 14b of the bottom tie plates are connected by a center filler casting 16, which has lateral extensions 16a lying in contact with and secured to the under surfaces of the sections 14b of the tie plates. A pair of diaphragms 17 lie between each bottom tie plate and the top cover plate 25 and each pair of diaphragms is connected by a stiffener 18 of inverted U-shape lying between and connected to the diaphragms. A stop plate 19 is secured to the inner face of each section 14d of a bottom tie plate.

The top plate, the sections 14c and 14d of the bottom tie plates, and the center filler casting 16 of each bolster define an opening and a rigid draft and buffering column 20 extends through the openings and from end to end of the underframe. The column is formed of a pair of Z-bars 20a having their top flanges secured edge to edge and the bottom flanges of the bars rest upon the lateral flanges 16a of the center filler castings of the two bolsters. The column is connected at each end to a coupler 21 by a key 22 and is acted on by the usual restoring means, which may take the form of a coil spring 23 disposed near each end of the column and encircling a link 24. Each spring bears at one end against a follower plate 25a, which engages an upward extension 26 from the center filler casting of the adjacent bolster and is engageable by stop plates 27 secured to the inner vertical walls of 40 the column. At its other end, the spring engages a follower plate 25b secured to plate 25a by link 24, which passes through an opening through plate 25b and has an enlarged head outside the plate. Normally, the plate 25b is held by the spring against the inner sides of 50 stop plates 28 carried by the column and the head of link 24 lies in engagement with one face of a follower plate 29, the other face of which is engaged by the end of the shank of the adjacent coupler 21. The column is provided with stop plates 30 mounted on the outer faces of 55 the vertical walls of the column on opposite sides of each bolster and in position to engage the stop plates 19 on sections 14d of the bottom tie plates of the bolster.

It will be apparent from the foregoing, that the new 60 bolster is simpler and less expensive to produce than the prior bolsters. The use of the bottom tie plates with the integral sections 14c, 14d, and 14e produces a strong rugged structure and the parts can be assembled with less labor than is required in making the prior bolsters. 65 The center filler casting is simpler than those previously used in that it does not include any vertical extensions and the use of the stop plates 19 and 30 on the bolster and column, respectively, for preventing the springs of the restoring means from going solid does not result 70 in the application of forces to the center casting which tend to rotate it. Accordingly, it is not necessary to em-

ploy torque arms and the cost of construction and the weight of the structure are correspondingly reduced.

I claim:

1. In a railway car underframe having side sills and an endwise movable rigid draft and buffering column extending substantially from end to end of the underframe and having bottom supporting flanges, a bolster, which comprises a top cover plate extending across the underframe from one side sill to the other and connected to the side sills, a bottom tie plate connected to and extending inward from each side sill, the tie plates having integral sections extending upward and defining opposite sides of an opening through the bolster for the column and terminating in end sections secured to the under surface of the top cover plate, a pair of diaphragms connecting the top cover and bottom tie plates, and a center filler member closing the bottom of the opening and having extensions secured to the tie plates outward from the integral sections thereof extending upward, the member supporting the column in its movements endwise through the opening.

2. The bolster of claim 1, in which the sections of the bottom tie plates extending upward have lower portions converging toward the top cover plate and overlying and spaced from the column flanges and upper portions, which are vertical.

5 3. The bolster of claim 1, in which the sections of the bottom tie plates secured to the under surface of the top cover plate extend outward toward respective side sills from the integral sections of the tie plates extending upward.

10 4. The bolster of claim 1, in which stops adapted to be engaged by stops on the column are mounted on the opposed faces of the sections of the tie plates extending upward.

15 5. The bolster of claim 4, in which the portions of the bottom tie plates carrying the stops are vertical.
